UNITED STATES PATENT OFFICE.

JOHN LAMBERT, JR., OF NEW ROCHELLE, AND HARRY B. LAMBERT, OF NORTH PELHAM,
NEW YORK.

VALVE.

1,274,426.

Specification of Letters Patent.

Patented Aug. 6, 1918.

Application filed February 26, 1917. Serial No. 151,029.

To all whom it may concern:

Be it known that we, JOHN LAMBERT, Jr., a citizen of the United States, residing at New Rochelle, in the county of Westchester and State of New York, and HARRY B. LAMBERT, a citizen of the United States, residing at North Pelham, in the county of Westchester and State of New York, have invented certain new and useful Improvements 5 in Valves, of which the following is a full, clear, and exact description.

This invention relates broadly to valves, but especially to those designed for use as inlet and exhaust-valves for fluid pressure 15 engines, motors, or pumps of any form or character, whether using liquids or gases under pressure; but is more especially designed and adapted for use in steam and explosive vapor motors, which valve of our 20 invention is of an extremely simple and cheap form of construction, of little liability to get out of order, of extreme durability and long life, and practically noiseless in its operation.

25 Our said invention is fully shown and described in the following specification, of which the accompanying drawing forms a part, wherein similar letters and numerals of reference designate like or equivalent parts 30 wherever found throughout the several views, and in which:

Figure 1 is a view in central vertical longitudinal section of an explosive vapor engine provided with an inlet-valve, and also 35 an exhaust valve, of our improved form; and

Fig. 2 is a view in detail, on an enlarged scale of one of our improved valves taken in the same central vertical section, of the form 40 shown in Fig. 1, the valve in Fig. 2, however, being inverted from the position shown in Fig. 1.

Referring to the drawing:

The reference letter A designates the cylinder of an explosive vapor engine, which 45 may be of many and various styles, provided with a water-cooling jacket-chamber B, connected with a cooling water supply, (not shown), in the usual manner; and having 50 the explosion chamber C in communication with an extension C' thereof, in which is located the usual ignition spark-plug D, but the foregoing mentioned structures may be 55 of any suitable desired form, and form no part of our invention,

As shown in Fig. 1, our improved valve, takes the place of the ordinary common poppet inlet and exhaust valve of the motor, and is inserted in place in substantially the same manner. The reference letter E indicates the inlet-valve, and E' the exhaust-valve, each of such valves being provided with an actuating shaft, rod or stem 11 and 11' respectively, each of which is reciprocated during the operation of the motor in 60 the well-known manner common to poppet and other reciprocating valves, but inasmuch as such reciprocating mechanism is well-known in the art and forms no part of this invention, we have not deemed it essential 65 to show or describe the same herein.

As shown in detail in Fig. 2, our improved valve comprises an inside stationary cylindrical wall member or valve-casing piece 2, formed integral with an annular end wall 2', 70 formed integral with a sleeve 2'', which member 2 is provided with an exterior annular male screw-thread 15, at the bottom by which the same is screwed firmly into position, at the base into a like shaped outer 75 cylindrical casing 1, of the same shape and contour as the casing 2, provided at its base adjacent to the screw thread 15 with a like outer annular male-screw thread 16 by which the same is secured in position in the female 80 screw-threaded port G or G', of the motor cylinder according as the same is to be an inlet or an exhaust valve.

The inner cylindrical member 2 is of shorter length than the outer cylindrical 90 member or shell 1, and a considerable space (according to the size of the valve used, from a half an inch upward), is left between the annular upper end wall 2' of 2, and the upper end wall 1' of 1, and contained and 95 secured in place between the two annular members or shells 1 and 2, is the moving valve-member or shell 3, having the cylindrical portion 3' fitting in the annular-space 100 17 between the annular-walls of 1 and 2, and having the end portion or wall 18, from the center of which extends the actuating lift-rod shaft or stem 11 or 11', actuated by suitable cam-mechanism of any suitable well-known form (not shown), which stem 105 11 or 11' is usually and preferably formed integral with the end wall 18 of the valve-member 3.

Located in the moving sleeve valve member 3 and the inner member 2 and forming 110

gas-tight joints between the moving sleeve valve member 3 and the inner-member 2, and the outer member 1, usually at the locations shown, are suitable piston-rings 7, 8, 5, 9, and 10, of any desired and suitable form, but in many cases and for certain purposes, such rings may be omitted and the joints made sufficiently tight by merely grooving the abutting surfaces. The cylindrical shell 10 or outer-member 1 is provided with a suitable port or ports in its periphery indicated by 4, and the inner cylindrical member or shell 2, is provided with a like port or ports 5, in registry with the port or ports 4 of 15 1: while the movable cylindrical valve-member 3, reciprocated up and down in the chamber 17, by the reciprocation of the valve-stem 11, is provided with a port or ports 6 adapted to be (upon such reciprocation) brought into and out of registry with the port or ports 5 of 2 and the port or ports 4 of 1, so as to permit of free passage of the fluids through all three of the ports 4, 5, and 6, when they are in registry, 20 and to shut off such passage as shown in Fig. 2, when out of registry.

In assembling and placing in position, the valve-stem (11 or 11'), is passed down through the sleeve 2'' after the placing in 30 position of the piston-rings 7, 8, 9, and 10, and the outer-sleeve 1 is then screwed into place; and the valve having been thus assembled, and the motor wall-plugs 20 and 20', (as the case may be), having been re- 35 moved, the valves are inserted through the orifices closed by such plugs, and screwed fully home in the female-thread by means of the exterior male screw-threads 16, in the motor engine-casing orifices; the sleeves 40 2'' and stem 11 or 11'' passing down through either the inlet 21 or the outlet 21', as the case may be; the entire valve mechanisms being firmly secured in place against 45 accidental displacement by a locknut 22 or 22' screwed upon the lower end of the sleeve 2''.

The valve mechanisms being now in position, it will be seen that by reciprocation of the stem 11 or 11', as the case may be, by 50 the usual valve stem-reciprocating mechanism (not shown), that the ports 4, 5, and 6, will be brought into and out of registry, so as to form communication or non-communication between the explosive chamber C 55 of the motor, and the inlet E or the outlet or exhaust E' thereof.

While we prefer to make our improved valve of cylindrical form, we do not limit ourselves to such construction and formation, and many changes in the construction and combination of the several parts, may be made without departing from the spirit and scope of our invention.

In like manner the positions of such valves 60 in the engine, pump, or other apparatus in

which the same may be used, may also be widely varied, and when used in double actuating engines or pumps, it is frequently preferable to have such valves actuated at a right angle to the axial line of reciprocation of the piston, instead of parallel therewith as shown in Fig. 1, as applied to an explosive vapor motor engine.

We claim:

1. In a valve, an outer casing closed at 75 one end and open at the other, having a ported-wall; an inner casing having an end-wall secured in the outer casing in such manner as to leave a space between such inner and outer casing between the end 80 walls of the two casings and having a ported side-wall spaced from the ported wall of the outer casing, the port or ports of which register with a port or ports in the wall of the outer casing; and a ported valve-member adapted to open and close the port passages of the inner and outer casings upon being moved, movably mounted in the space between the inner and outer casings.

2. In a valve, an outer casing closed at one 90 end and open at the other, having a ported-wall; an inner casing having an end-wall secured in the outer casing in such manner as to leave a space between such inner and outer casing between the end walls of the 95 two casings and having a ported side-wall spaced from the ported wall of the outer casing, the port or ports of which register with a port or ports in the wall of the outer casing; and a ported valve-member adapted 100 to open and close the port passages of the inner and outer casings upon being moved, reciprocatingly movably mounted in the space between the inner and outer casings.

3. In a valve, a casing comprising an 105 inner casing-member having a centrally perforated wall carrying an annular ported wall extending at a right-angle thereto; a like-shaped outer casing-member secured at its open end to the peripheral outer end of the inner casing member, the end wall of the outer casing member being imperforate and the annular wall thereof having a port or ports registering with the port or ports in the annular wall of the inner casing member; a like shaped moving valve-member, provided in the annular wall with a port or ports adapted to be brought into and out of registry with the port or ports of the inner and outer casing walls; and a valve-stem connected with the valve-member extending through the perforation in the wall of the inner casing member and out through the casing for moving the valve-member.

4. In a valve, a casing comprising an 125 inner casing-member having a centrally perforated wall carrying an annular ported wall extending at a right-angle thereto, a sleeve extending from the perforation of said inner wall, a like-shaped outer casing-mem- 130

- ber secured at its open end to the peripheral outer end of the inner casing member, the end wall of the outer casing member being imperforate and the annular wall thereof having a port or ports registering with the port or ports in the annular wall of the inner casing member; a like-shaped moving valve member, provided in the annular wall with a port or ports adapted to be brought 10 into and out of registry with the port or ports of the inner and outer casing walls; and a central valve-stem connected with the valve-member for reciprocatingly actuating the same passing out through said sleeve.
- 15 5. In a valve, a casing comprising an inner casing-member having a centrally perforated wall carrying an annular ported wall extending at a right-angle thereto, a sleeve extending outward from the perforation of 20 said inner wall; a like-shaped outer casing-member secured at its open end to the peripheral outer end of the inner casing member, the end wall of the outer casing member being imperforate and the annular wall thereof having a port or ports registering with the port or ports in the annular wall of the inner casing member; a like-shaped moving valve member provided in the annular wall with a port or ports adapted to be brought 25 into and out of registry with the port or ports of the inner and outer casing walls, and a central valve-stem connected with the valve-member for reciprocatingly actuating the same passing out through said sleeve; the joints between the faces of the 30 valve-member and the abutting faces of the inner and outer casing-members forming the valve chamber, being rendered air-tight by suitable packing.
- 35 6. In a valve, a casing comprising an inner casing-member having a centrally perforated wall carrying an annular ported wall extending at a right-angle thereto, a sleeve extending outward from the perforation of 40 said inner wall; a like-shaped outer casing-member secured at its open end to the peripheral outer end of the inner casing member, the end wall of the outer casing member being imperforate and the annular wall thereof having a port or ports registering with the port or ports in the annular wall of the inner casing member; a like-shaped moving valve member, provided in the annular wall with a port or ports adapted to be 45 brought into and out of registry with the port or ports of the inner and outer casing walls; and a central valve-stem connected with the valve-member for reciprocatingly actuating the same passing out through said 50 sleeve; the joints between the faces of the valve-member and the abutting faces of the inner and outer casing-members forming the valve chamber, being rendered air-tight by suitable packing.
- 55 7. In a valve, a casing comprising an inner casing-member having a centrally perforated wall carrying an annular ported wall extending at a right-angle thereto, a sleeve extending outward from the perforation of 55 said inner wall; a like-shaped outer casing-member secured at its open end to the peripheral outer end of the inner casing member, the end wall of the outer casing member being imperforate and the annular wall thereof having a port or ports registering with the port or ports in the annular wall of the inner casing member; a like-shaped moving valve member, provided in the annular wall with a port or ports adapted to be 60 brought into and out of registry with the port or ports of the inner and outer casing walls; and a central valve-stem connected with the valve-member for reciprocatingly actuating the same passing out through said sleeve, the outer casing being provided with an outer annular male screw-thread for securing the same in position.
- 65 8. In a valve, a casing comprising an inner casing-member having a centrally perforated wall carrying an annular ported wall 70 extending at a right angle thereto, a sleeve extending outward from the perforation of said inner wall, a like shaped outer casing member secured at its open end to the peripheral outer end of the inner casing member, the end wall of the outer casing member being imperforate and the annular wall thereof having a port or ports registering with the port or ports in the annular wall of the inner casing member, a like shaped moving valve member provided in the annular wall with a port or ports adapted to be brought 75 into and out of registry with the port or ports of the inner and outer casing walls, and a central valve-stem connected with the valve-member for reciprocatingly actuating the same passing through said sleeve, the outer casing being provided with an outer annular male screw-thread for securing the same in position, and the valve-stem-sleeve being provided with a like screw-thread for the reception of a securing nut.
- 90 9. In a valve, an outer casing closed at one end by an end wall and open at the other end, an inner casing having an end wall secured in the outer casing and spaced from the end wall of said outer casing, and a valve member having a disk portion reciprocably mounted between said end walls, the disk portion and casings forming closed air chambers on either side of said disk portion so that the air in said air chambers will form air cushions to resiliently resist the action of said disk portion and the thereto-connected valve-member, there being 95 registering ports in said casings and valve member, and means for actuating said disk portion to bring the ports of said valve member and casings either into or out of registration.
- 100 10. In a valve, an outer casing closed at one end by an end wall and open at the other end, an inner casing having an end wall secured in the outer casing and spaced from the end wall of said outer casing, a valve member having a disk portion reciprocably mounted between said end walls, the disk portion and casings forming closed air chambers on either side of said disk portion so that the air in said air chambers will form air cushions to resiliently resist the action of said disk portion and the thereto-connected valve member, there being 105 a perforation through one of said end walls, and a stem connected to said disk portion extending through said perforation outwardly from said air chambers to be there connected for actuation, there being registering ports in said casings and valve member, and means for actuating said disk portion to bring the ports of said valve member and casings either into or out of registration.
- 110 11. In a valve, an outer casing closed at one end by an end wall and open at the other end, an inner casing having an end wall secured in the outer casing and spaced from the end wall of said outer casing, a valve member having a disk portion reciprocably mounted between said end walls, the disk portion and casings forming closed air chambers on either side of said disk portion so that the air in said air chambers will form air cushions to resiliently resist the action of said disk portion and the thereto-connected valve member, there being 115 a perforation through one of said end walls, and a stem connected to said disk portion extending through said perforation outwardly from said air chambers to be there connected for actuation, there being registering ports in said casings and valve member, and means for actuating said disk portion to bring the ports of said valve member and casings either into or out of registration.
- 120 12. In a valve, an outer casing closed at one end by an end wall and open at the other end, an inner casing having an end wall secured in the outer casing and spaced from the end wall of said outer casing, a valve member having a disk portion reciprocably mounted between said end walls, the disk portion and casings forming closed air chambers on either side of said disk portion so that the air in said air chambers will form air cushions to resiliently resist the action of said disk portion and the thereto-connected valve member, there being 125 a perforation through one of said end walls, and a stem connected to said disk portion extending through said perforation outwardly from said air chambers to be there connected for actuation, there being registering ports in said casings and valve member, and means for actuating said disk portion to bring the ports of said valve member and casings either into or out of registration.
- 130 13. In a valve, an outer casing closed at one end by an end wall and open at the other end, an inner casing having an end wall secured in the outer casing and spaced from the end wall of said outer casing, a valve member having a disk portion reciprocably mounted between said end walls, the disk portion and casings forming closed air chambers on either side of said disk portion so that the air in said air chambers will form air cushions to resiliently resist the action of said disk portion and the thereto-connected valve member, there being a perforation through one of said end walls, and a stem connected to said disk portion extending through said perforation outwardly from said air chambers to be there connected for actuation, there being registering ports in said casings and valve member, and means for actuating said disk portion to bring the ports of said valve member and casings either into or out of registration.

wall secured in the outer casing and spaced from the end wall of said outer casing, a valve member having a disk portion reciprocably mounted between said end walls, the disk portion and casings forming closed air chambers on either side of said disk portion so that the air in said air chambers will form air cushions to resiliently resist the action of said disk portion and the thereto-connected valve member, there being registering ports in said casings and valve member, and means for actuating said disk portion to bring the ports of said valve member and casings either into or out of registration.

11. In a valve, an outer casing closed at one end by an end wall and open at the other end, an inner casing having an end wall secured in the outer casing and spaced from the end wall of said outer casing, a valve member having a disk portion reciprocably mounted between said end walls, the disk portion and casings forming closed air chambers on either side of said disk portion so that the air in said air chambers will form air cushions to resiliently resist the action of said disk portion and the thereto-connected valve member, there being ports in registration with one another in said casings, there being ports in said valve member, and means operatively connected to said disk portion for actuating said disk portion

to bring the ports of said valve member either into or out of registration with the ports of said casings.

12. In a valve, an outer casing closed at one end by an end wall and open at the other end, an inner casing having an end wall secured in the outer casing and spaced from the end wall of said outer casing, a valve member having a disk portion reciprocably mounted between said end walls, the disk portion and casings forming closed air chambers on either side of said disk portion so that the air in said air chambers will form air cushions to resiliently resist the action of said disk portion and the thereto-connected valve member, there being a perforation through one of said end walls, and a stem connected to said disk portion extending through said perforation outwardly from said air chambers to be there connected for actuation, there being ports in registration with one another in said casings, there being ports in said valve member, the stem being actuatable to in turn actuate the disk portion to bring the ports of said valve member either into or out of registration with the ports of said casings.
